UNITED STATES PATENT OFFICE.

FRED ALDINGER, OF ACKLEY, IOWA.

JACK.

Application filed May 20, 1926. Serial No. 110,401.

This invention relates to improvements in jacks, and has for its principal object to provide a lifting jack to be used in connection with tractors.

5 Another object of the invention is to provide a jack, mounted on a base, said jack being slidable on said base whereby it may be adjusted.

A still further object of the invention is to 10 provide a lifting jack having means whereby it may be manually adjusted either vertically or horizontally beneath the axle of a tractor, or other vehicle.

Another object of the invention is to 15 provide a base, having a plurality of lifting jacks thereon, one of said jacks being stationary on said base, and another of said jacks being slidable thereon, by means of rollers.

20 A still further object of the invention is to provide a base, having a stationary jack on one end thereof, adapted to hold the rear end of a tractor, or other mechanism, and an adjustable jack on the front end thereof, 25 adapted to receive the radius rod of the tractor and move the front part of the tractor forward or backward, and both of said jacks being provided with means whereby they may be manually operated to elevate 30 said tractor.

Another object of the invention is to provide in combination with a jack of this character, a wedge for steadyng the front axle of the tractor, in order to prevent the same 35 from tipping sideways.

In the drawings wherein I have shown the preferred embodiment of my invention,

Figure 1 is an elevational view of my improved jack;

40 Figure 2 is a top plan view thereof;

Figure 3 is a sectional view on line 3—3 of Figure 1;

Figures 4 and 5 are detail views of adjustments;

45 Figure 6 is a view in elevation of the movable jack;

Figure 7 is a front elevational view of the stationary jack;

Like reference characters indicate like 50 parts throughout the following specification, and in the several views in the drawings in which: 1 indicates my improved lifting jack, which consists of a base 2, formed of three channel irons, 3, 4 and 5, said channel iron 55 sections, being connected together by means of screws, bolts, rivets, or the like. Fixedly

mounted on one end of said base 2, is a plate 6, forming a base for the internally screw threaded section 7, of the jack, adapted to receive the screw 8, having right angularly 60 disposed bores therethrough, whereby a handle may be readily inserted for operating the jack.

This jack is provided with an arcuate surface 9, in order to readily accommodate the 65 rear end of a tractor, or other device. A lug 10 is provided on the upper surface of the plate 6, and a similar lug 11 is provided on the under surface of said plate, said lugs having internally, screw threaded bores 12 70 and 13 therein, adapted to receive the screws 14 and 15, projected through the block 16, in order to hold the same in place. This block has an opening, through which the gear shaft 18 is adapted to project a gear wheel 75 19 is fixed to said shaft, and is adapted to mesh with the similarly formed gear wheel 20, rotatably mounted in projection 21, on the lower side of said plate 6. The gear wheel 20, is adapted to operate a rod 22, 80 which rod is screw threaded within the lug 23, on the undersurface of the jack 24, said jack being slidably mounted on the base 2, by means of rollers 25, 26, 27, and 28, and being adjustable by means of the gear wheels 85 19 and 20, adapted to be rotated by means of the handle 29.

The adjustable jack 24, is provided with a wedge shaped surface 31, adapted to fit over the radius rod of the tractor, whereby 90 the front end of the tractor may be moved backward and forward, by means of the adjustment of the jack 24.

An attachment 32, is provided, the same being of such a shape as to be readily fit 95 within the wedge shaped members 31, whereby the adjustable jack may be used on the rear end of the tractor or other vehicle, if desired.

A wedge 33, is provided for steadyng the 100 tractor in upright position, in order that it will be prevented from tipping sideways. This wedge is adapted to fit on the front axle of a tractor, the same being adjustable by means of the bolt 34, having a nut 35 105 thereon for tightening the same in position.

In the operation of my device, nut 35 is unscrewed and the wedge portions 33 are drawn apart. The wedge portions 33 are then placed upon the top of the front axle 110 of the structure between the front axle and the body portion of the tractor. Nut 35 is

then tightened thus drawing the wedge portions 33 together so that the body portion of the tractor will be held in a rigid position with relation to the front axle and will not allow the body portion of the tractor to fall to one side when the bolts which are located near the central portion of the tractor are unbolted in order to make repairs to the transmission of the tractor. The jack is then placed underneath the tractor with rear jack 9 under the rear axle housing of the tractor and front jack 24 underneath the radius rods of the front portion of the tractor. The jacks 9 and 24 are then raised by inserting a suitable tool through the openings in the jacks and rotating such tools. The bolts at the central portion of the tractor may then be unbolted and the crank handle 29 rotated in order to move the front portion of the tractor fifteen or twenty inches forward from the rear portion of the tractor and thus enable one to repair the parts of the transmission.

This jack is adapted to be used either on tractors, or automobiles, and is readily applied to shop work, or field work.

It will thus be seen that I have provided an adjustable jack, by means of which the front wheels of a tractor may be locked in upright position, whereby the front or rear end of the same may be lifted, and the different parts repaired, as required.

Having described my invention that which I claim to be and desire to procure by Letters Patent is:

1. A jack structure comprising a base, a plurality of jacks comprising a rear jack

and a front jack mounted thereon, said rear jack being adapted to support the rear of a tractor and said front jack being adapted to support the front of a tractor, and means placed on the front axle of said tractor between said axle and the body portion of said tractor to maintain said body portion in upright position when said tractor is unbolted at its center.

2. A jack structure comprising a base, a plurality of jacks comprising a rear jack and a front jack mounted thereon, said rear jack being adapted to support the rear end of a tractor and said front jack being adapted to support the front of a tractor, and a wedge device placed on the front axle of said tractor between said axle and the body portion of said tractor to maintain said body portion in upright position when said tractor is unbolted at its center.

3. A jack structure comprising a base, a plurality of jacks comprising a rear jack and a front jack mounted thereon, said rear jack being adapted to support the rear of a tractor and said front jack being adapted to support the front of a tractor, and an adjustable wedge device comprising two wedge portions and means for adjusting said wedge portions toward and away from each other placed on the front axle of said tractor between said axle and the body portion of said tractor to maintain said body portion in upright position when said tractor is unbolted at its center.

In testimony whereof I affix my signature.

FRED ALDINGER.
